By B. Singer, Atty

UNITED STATES PATENT OFFICE

ROBERT FUST, OF GLOGAU, GERMANY

MATRIX FOR USE IN DENTISTRY

Application filed September 12, 1929, Serial No. 392,221, and in Germany September 21, 1928.

My invention relates to improvements in matrices for use in dentistry, and more particularly in matrices of the type used for covering the cavity of a tooth while filling the same. As now constructed such matrices consist of sheet metal rings or open sheet metal rings adapted to be placed around the sick tooth. The object of the improvements is to provide a matrix which is simple in construction, which fits on teeth of any size, and which provides a close covering for the cavity to be filled. With this object in view my invention consists in constructing the matrix in the form of a thin elastic plate of a suitable material such as steel adapted to be placed between the sick tooth and the adjacent tooth and provided along its vertical margins with ribs or similar projections adapted to bear on the healthy tooth and to press the plate into close contact with the sick tooth. My invention also relates to a tool suitable for placing the matrix in position on the sick tooth.

Other objects of the improvements will appear from the following description.

For the purpose of explaining the invention an example embodying the same has been shown in the accompanying drawings in which the same reference characters have been used in all the views to indicate corresponding parts. In said drawing,

Fig. 1 is a sectional plan view of the matrix taken on the line 1—1 of Fig. 3,

Fig. 2 is a sectional elevation taken on the line 2—2 of Fig. 1,

Fig. 3 is an elevation showing the matrix as seen from the side of the healthy tooth,

Fig. 4 is a perspective view showing the sick tooth, the adjacent healthy tooth and the matrix brought into position for covering the cavity of the sick tooth, and

Fig. 5 is a perspective view showing a tool used for bringing the matrix into position.

In the example shown in the drawings the matrix consists of a thin plate 1 made from thin sheet metal such as steel and provided along its vertical margins with ribs or similar projections 2 provided between their top and bottom ends with recesses 3. At their inner

faces 10 the projections or ribs are curved outwardly, so that the ribs are crescent-shaped in cross-section, and the median portions of the ribs bounding the recesses 3 are bevelled inwardly and towards the plate 1, as is shown at 11. The ribs are formed at the side bearing on the gum with concave recesses 4 adapted to bridge the upwardly directed parts of the gum between the teeth. In Fig. 2 in which the matrix is shown in the position in which it is placed between teeth of the lower set the recesses 4 are located at the bottom sides of the ribs, and it will be understood that when placing the matrix between upper teeth it is reversed so that the cavity 4 bears on the gum.

The manner of using the matrix has been illustrated in Fig. 4. In the said figure the plate 1 is placed between a healthy tooth 5 and the sick tooth 6 so as to cover the cavity 7. The ribs 2 bear on the healthy tooth and they press the plate 1 laterally and into close contact with the sick tooth 6, the plate being slightly curved by the pressure of the ribs. If necessary cotton may be pushed through the recesses 3 and between the bevelled portions 11 of the ribs 2 and the healthy tooth 5 for securely pressing the plate 1 on the tooth 6. The figures show screws 12 screwing in bores 13 of the ribs. By screwing the said screws more or less inwardly and into engagement with the healthy tooth the plate 1 may be pressed on the sick tooth for securely closing the cavity.

For pressing the matrix on the sick tooth I use an angular tool shown in Fig. 5, the said tool comprising a handle 8 and a portion 9 in the form of a spade bent laterally from the handle. The said spade portion may be placed between the plate 1 and the tooth 5, and thereafter the spade is slightly turned for pressing the plate 1 towards the tooth 6.

In describing the invention reference has been made to the manufacture of the matrix from sheet steel. But I wish it to be understood that my invention is not limited to this feature, and that the matrix may be manufactured from other suitable material such as celluloid or other cellulose products.

I claim:

1. A dental matrix comprising a thin elastic plate for insertion in the space between two teeth and inelastic ribs on one face of said plate, said ribs having recesses to facilitate the introduction of material through the ribs.
2. A matrix as claimed in claim 1, in which the plate is concavo convex cross sectionally and the ribs project from the convex face thereof and serve to hold the plate in such flexed condition.
3. A matrix as claimed in claim 1, in which the bottoms of the recesses in the ribs are bevelled toward the plate.
4. A matrix as claimed in claim 1, in which the ribs are provided on the sides opposed to the gum when the matrix is in use, with recesses for spanning the gum.
5. A matrix as claimed in claim 1, in which the opposing sides of the ribs are convex in form.

In testimony whereof I hereunto affix my signature.

ROBERT FUST.
